UNITED STATES PATENT OFFICE.

THOMAS J. CLINTON AND DONALD AGROFF, OF WOODSTOCK, ONTARIO,
CANADA.

MACHINE FOR SCRAPING AND SPLITTING RATTAN.

SPECIFICATION forming part of Letters Patent No. 308,139, dated November 18, 1884.

Application filed November 21, 1883. (No model.)

To all whom it may concern:

Be it known that we, THOMAS J. CLINTON and DONALD AGROFF, of Woodstock, in the county of Oxford and Province of Ontario, 5 Canada, have invented new and useful Improvements in Rattan Scraping and Splitting Machines; and we do hereby declare that the following is a full, clear, and exact description thereof, reference being had to the accompanying drawings, which form a part of this specification.

This invention relates to certain new and useful improvements in the construction of machines designed for squaring the ends of 15 rattan or cane, and for scraping and splitting the same preparatory to its use in the manufacture of the many articles which are constructed principally from the pith and strands of rattan.

20 To that end the invention consists, first, in the peculiar construction of devices for squaring the ends of the cane before it is passed to the other operating parts of the device; second, in the peculiar construction and arrangement 25 of the scraping-knives and devices for feeding the cane thereto, such construction being entirely automatic in its operations; third, in the peculiar construction and arrangement of the splitting-knife, whereby the shell of the 30 cane is separated into strands of equal widths from the pith, and in the peculiar means employed for giving both vertical and lateral adjustment to these knives; and, fourth, in the peculiar construction, arrangement, and various 35 combinations of the parts, all as more fully hereinafter set forth.

Figure 1 is a top plan of our improved machine. Fig. 2 is a side elevation of the same. Fig. 3 is an elevation of the scraper, showing 40 devices for automatically operating the knives, the device being in the position shown to receive the cane. Fig. 4 is a rear elevation, partially in section, showing the devices for automatically controlling the knives, said devices being shown in their relative positions 45 during operation. Fig. 5 is a central cross-section on the line X X in Fig. 3. Fig. 6 is an end view of the pith-catcher. Fig. 7 is an elevation of the spring-guide. Fig. 8 is a detached perspective of cane-splitter and attachments.

In the accompanying drawings, A represents a suitable frame which carries the operating parts of our machine. At the front end of this frame, and near one side thereof, is 55 properly journaled in boxes the horizontal shaft B, which derives motion from intermeshing gears with any convenient shaft of the machine. The forward end of this shaft carries a rotating cutter-head, C, the knives of which 60 come in close proximity to the inner face of the front gear of the frame, through which latter is placed a mouth-piece, B', through which, in the operation of the machine, the end of the cane to be operated upon is inserted, so 65 that the rotating cutter-head cuts off square that end of the cane.

70 D are vertical shafts, the upper ends of which are designed to yield against the pressure of a spring-box, as shown in dotted outlines at the right-hand or front end of the machine in Fig. 1, and upon the upper ends of these vertical shafts are secured the feed-rolls E, around the periphery of each of which is formed a small and a large grooved channel. The lower ends 75 of these shafts D are stepped in thimbles F, each of which carries or is provided with an adjusting-screw, *a*, in its lower end, and by means of which the shafts are raised or lowered in order to adjust the feed-rollers to the 80 proper plane. Motion is communicated to these shafts D by means of a chain of intermeshing gears, G, receiving their initiatory movement or motion from a gear upon the main shaft H, which in turn receives its motion from any suitable power. 85

I represents the scraper-head, which carries the scraper-knives *b*. These knives are arranged in sufficient numbers to entirely surround the central feedway through the scraper-head, and they are arranged in pairs, in each of which one knife is opposite the other, so that all portions of the circumference of the knot or joint of the cane which need to be scraped off are operated upon. These knives 90 are properly secured in supporting-blocks *c*, which are arranged to slide laterally and radially in recesses in the face of the scraper-head. The rear ends of these blocks terminate in hollow tangs or arms *d*, within which 95 is placed a coil-spring, *e*, Figs. 3 and 5, the tension of which is adjusted or regulated by 100

an adjusting-screw, *f*, the function of such spring being to compel the knives to come in contact with the cane as it passes through the scraper-head, and the radial sliding movement or opening of the knives is necessary in order that the end of the cane may enter between them, and this opening of the knives we perform automatically by the means and devices which we will now proceed to describe.

J is a bottom plate of the scraper-head, which is rigidly secured thereto by proper bolts, and is provided with radial slots *g*, through which bolts *h* pass and engage with the bottom of the spring-blocks *c*. Between this bottom plate, *J*, and the scraper-head *I*, the latter of which is recessed upon the back to receive it, we place a wheel or plate, *K*, the periphery of which is formed into a series of cams, *i*. This wheel *K* is provided with an arm, *j*, which projects beyond the edge of the scraper-head and engages with a worm, *L*, upon the upper end of the shaft *M*, the lower end of which is journaled in the same manner as the lower ends of the shafts *D*, while the upper end is journaled in a spring-box, as shown in Fig. 3, so as to compel at all times an engagement between the arms *j* and the worm *L*, excepting as hereinafter described.

In the rear face of the bottom plate, *J*, of the scraper-head we properly secure the tripping device or block *N*, which consists of a circular or two semicircular blocks, one of which has secured to it the bar *O*, which is regulated by the adjusting-screw *k*, while to the other half of the tripping-block we secure a bar, *P*, the end of which projects beyond the edge of the scraper-head, and is provided with an arm, *l*, which is designed to come in contact with the upper end of the shaft *M*, as hereinafter described. The front end of the tripping-block *N* is recessed at *m*, Fig. 5.

Q are guide-plates placed between the feed-rolls, as shown, each plate being provided with an upwardly-projecting standard, through which is secured a guide-tube, *n*, in the longitudinal direction of the machine.

R are adjustable spring-guides placed, respectively, in front of the scraper-head and splitter-knife. These guides are constructed in two parts, each part consisting of the elbow guide-levers *R'*, (shown in Fig. 7,) having their vertical arms pivotally secured to the plate *R''*, which in turn is rigidly secured to the bed of the machine. The tension of these guide-levers is regulated by coil-springs *o* around the adjusting-bolts *R'''*, Fig. 7, which pass through the free ends of the same, the tension of such springs being designed to keep the free or meeting faces of the guide-clamp against the cane as it passes through the machine.

S represents the stripping device and sides of a cylinder-knife, having radial knives projecting therefrom, and is substantially the same as the knife used for a similar purpose

in that class of machinery. The knife *S* is supported upon a block, *p*, the lower face of which is provided with a dovetailed recess, *s'*, which slips over the dovetail *r* upon the upper face of the screw *T*, which is threaded in the cup *T'*, a bolt, *T''*, passing through the bottom of such cup from the screw *T*, and through the bed of the machine, receiving a nut, *T'''*, upon its lower end, which locks the various devices to their adjusted positions.

In the dovetailed recess in the under face of the block *p* is a depending lug, *s*, through which a thumb-screw is threaded, such screw passing through one end of the hollow dovetail *r*, so that when the parts are together, as shown in Fig. 2, the splitting-knife may be adjusted laterally across the machine, as may be desired. When a vertical adjustment is desired, the nut upon the lower end of the bolt *T''* is loosened, when the knife or splitting device *S* is held with one hand, while the sleeve *T'* is turned so as to raise or lower the splitting device, as circumstances may require.

At the rear end of the machine, and at the right hand thereof, we pivotally secure a lever, *V*, one end of which is connected by an arm to the shaft of the rear right-hand guide-roll, while the opposite end is secured by means of a ball-and-socket joint to a pawl, *W*, which engages with a ratchet, *X*, upon the shaft of the pith-catcher *Y*, which is properly journaled upon the shaft at the rear of the machine, and in a line with the guides, such pith-catcher being composed of a corrugated cylinder, beneath which is located a bracket or brackets, which catch all pith as it is discharged from this cylinder, the parts being so arranged that as the cane passes through the machine it enters between the two rollers at the rear of the machine. The right-hand roller is necessarily forced outward, which causes the pawl *W* to push or partially rotate the ratchet *X* and the pith-catcher, so that one of the corrugations will come directly opposite the discharge end of the machine, into which the pith passes, between it and the bed-bar *Z*, which supports the brackets, and after it has so passed the guide-wheel again resumes its original position until it is again forced outward by the succeeding pith, which causes the pith-catcher to again partially rotate, and so on, presenting a new corrugation of the pith-roller at each operation, and as the pith-catcher continues in its rotation the pith drops out of the corrugations into the brackets hereinbefore described.

In practice, after the ends of the cane have been squared off by the rotating cutter *C*, the end of the cane is fed into the mouth of the feed-tube *Y'* until it is grasped by the first series of grooved feed-rolls *E*, from whence it is fed by them into the tube *n* of the guide *Q*, thence between the next pair of feed-rolls and through between the guides *R*, the spring *o* of which is so arranged as to clamp or embrace the cane and feed or direct the end of the cane

into the scraper-head between the knives *b*. As the end of the cane comes in contact with the trip *N* it forces the two halves of such trip apart, the bar *O* yielding slightly against the set-screw *k* and inclosed spring, while the bar *P* yields or slides outwardly until its arm *l* comes in contact with the head of the shaft *L* and pushes the same into the position shown in Fig. 4 from that shown in Fig. 3, in which 5 to position the arm *j* of the wheel *K* is disengaged from the worm *L*, when the action of the springs *e* of the knife-blocks causes the knives to close sufficiently close together so as to 10 scrape off and remove the knots or joints of the cane as it continues to pass through, while at the same time the wheel *K* is, by the action of the pins *h* sliding upon the cams *i*, partially rotated, so that while the cane is passing through the scraper the arm and wheel as 15 20 sume the position shown in Fig. 4. As soon as the cane passes entirely through the scraper-head and trip *N*, then the spring-box *M'* of the shaft *M* causes such shaft to assume the position shown in Fig. 3, the end of the arm *j* engaging with the lower portion of the worm 25 30 *L* upon such shaft, which is continually revolving. The arm *j* travels up the worm until it passes through the gate *w* of such worm, when, in the continued rotation of the shaft 35 and worm, the arm rests upon the top of the worm. This action of parts causes the wheel *K* to partially rotate, and compels the pins *h* to slide up the cams *i* and retract the scraper-knives, holding them in this position until 40 another cane is inserted and disengages the arms *j* from the worm *L*, as herein just described. By this construction and arrangement of parts it will be seen that the scraper-knives are open at all times excepting during 45 the period that a cane is passing through the scraper-head, and that they are advanced and retracted automatically and by the insertion and passage of the cane through the machine. From the scraper-head the cane passes through 50 between the series of feed-rolls *E* and guides to the rear guide, *R'*, which directs the cane centrally to the knife *S*, the pith passing through the knife and through the tubular guide *r'* at the end thereof, to and between the rear sets of 55 guide-wheels and guides, from whence it is discharged from the machine into the pith-catcher, while the strands which are stripped or cut from the exterior of the cane pass into the upwardly-curved guide *y*, formed by the block *p*, and are thrown from the machine.

By having the feed-rolls *E* provided with a large and a small groove, and through the medium of the adjustments provided for the

shafts *D*, it can readily be seen that the feed-rolls can be raised or lowered to suit the size 60 of cane to be operated upon.

It will be observed that the stripping-knife can also be accurately adjusted vertically and laterally, so that the cane must necessarily be centrally presented to the action of the knife 65 as it leaves the guides *R'*.

What we claim as our invention is—

1. In a rattan scraping and splitting machine, and as a means for automatically opening and closing the knives of the scraper-head, 70 the combination of the head *I*, plate *J*, between which is placed the wheel *K*, the periphery of which is provided with an arm, *j*, and a series of cams, *i*, the latter being adapted to actuate the knife-blocks *c*, with the worm 75 *L* upon the yielding shaft *M*, and any suitable automatic tripping device, substantially as and for the purposes set forth.

2. As a means for automatically opening and closing the scraper-knives, the combination of 80 the scraper-head *I*, provided with the yielding blocks *c*, carrying the knives *b*, cam-wheel *K*, arranged between the head *I* and plate *J*, and provided with the arm *j*, pins *h*, rigidly secured to the blocks *c*, and the tripping device *N*, secured to the bottom plate, and carrying the arm *l*, with the worm *L*, carried by the yielding shaft *M*, spring-box *M'*, and springs 85 *e*, all arranged and operating substantially as set forth. 90

3. In a rattan scraping and splitting machine, and as a means for vertically adjusting the stripping-knife, the combination of the block *p*, carrying the splitting-knife *S'*, with the screw *T*, cup *T'*, bolt *T''*, and nut *T'''*, arranged as specified, whereby the said knife 95 is vertically adjustable, substantially as described.

4. In a rattan scraping and splitting machine, the combination of the block *p*, having 100 the dovetailed recess *s'* and depending lug *s*, hollow dovetail *r*, and adjusting-screw *u*, arranged as described, whereby a lateral adjustment is given to the stripping-knife, substantially as set forth. 105

5. An improved guide in a rattan scraping and splitting machine, consisting of the elbow guide-levers *R'*, having their vertical arms pivotally secured to the bed-plate *R²* and their free ends under tension, substantially as and 110 for the purpose specified.

THOMAS J. CLINTON.
DONALD AGROFF.
